(57) **CLAIM**

The ornamental design for a fare collection machine, as shown and described.

DESCRIPTION

FIG. 1 is a front, top and right side perspective view of a fare collection machine showing our new design, in which the bill tray is pivoted to a vertical position;
FIG. 2 is a front, top and left side perspective view thereof;
FIG. 3 is a front elevational view thereof;
FIG. 4 is a rear elevational view thereof;
FIG. 5 is an enlarged top plan view thereof;
FIG. 6 is a right side elevational view thereof;
FIG. 7 is a left side elevational view thereof;
FIG. 8 is an enlarged front, top, right perspective view of the portion indicated by lines 8-8 in FIG. 1;
FIG. 9 is an enlarged front, top, left perspective view of the portion indicated by lines 9-9 in FIG. 2;
FIG. 10 is an enlarged front view of the portion indicated by line 10-10 in FIG. 3;
FIG. 11 is an enlarged cross-sectional view taken along line 11-11 in FIG. 5 with the internal structure omitted;
FIG. 12 is an enlarged cross-sectional view taken along line 12-12 in FIG. 10 with the internal structure omitted;
FIG. 13 is an enlarged top plan view thereof, in which the bill tray is pivoted to a horizontal position;
FIG. 14 is an enlarged perspective view of the portion shown in FIG. 8, in which the bill tray is pivoted to the horizontal position;
FIG. 15 is an enlarged perspective view of the portion shown in FIG. 9, in which the bill tray is pivoted to the horizontal position;
FIG. 16 is an enlarged front view of the portion shown in FIG. 10, in which the bill tray is pivoted to the horizontal position;
FIG. 17 is an enlarged cross-sectional view taken along line 17-17 in FIG. 13 with the internal structure omitted, in which the bill tray is pivoted to the horizontal position; and
FIG. 18 is an enlarged cross-sectional view taken along line 18-18 in FIG. 16, in which the bill tray is pivoted to the horizontal position.
The features shown in broken lines in the drawings depict environmental subject matter only and form no part of the claimed design.
